UNITED STATES PATENT OFFICE.

FREDRICK G. EVANS, OF OAK PARK, ILLINOIS, ASSIGNOR TO CHICAGO FLEXIBLE SHAFT COMPANY, OF CHICAGO, ILLINOIS, A CORPORATION OF ILLINOIS.

SHEEP SHEARS.

Application filed August 27, 1927. Serial No. 215,965.

The purpose of this invention is to provide a sheep shear and like tools having a fixed comb and reciprocating cutter blade, lever-actuated, in which the engagement of the reciprocating blade by the lever may be affected by a plurality of projections co-operatively situated on the lever for entering the recesses in the blade, and in which the registration of the projections with the recesses may remain accurate for avoiding lost motion or liability to disengagement in the reciprocation of the blade, notwithstanding slight variations due to expansion and contraction of the parts by change of temperature, or to unavoidable inaccuracies in the original formation. The invention consists in the elements and features of construction shown and described as indicated in the claims.

In the drawings:

Figure 1 is a plan view of a power-driven manually directed sheep shear embodying this invention.

Figure 2 is a section at the line 2—2 on Figure 1.

Figure 3 is a top plan view of the reciprocating blade.

Figure 4 is an inverted plan view of the lever by which the blade is engaged for reciprocation.

Figure 5 is a detail section at the line 5—5 on Figure 4.

Referring to the drawings, A is the comb and fixed cutter of a sheep shear embodying this invention being rigid with the body or casing, B, which terminates the hand-piece, C, in which is mounted pivotally at 10 the operating lever, D, engaged at the rear end by the crank wrist, 11, of the crank arm, 12, of the rotating shaft, 13, journaled in the customary manner in the hand-piece, C, and rotated by the usual connections, not shown, to a flexible power shaft not shown. 14 is the customary pressure pin, sometimes called a dolly pin, through which pressure from the pressure spring, 20, is transmitted to the pressure fork, F, and through said pressure fork to the lever, D, for holding the reciprocating blade pressed upon the fixed cutter blade, A, properly for the shearing action.

The operating lever, D, is extended laterally at the forward end in two divergent pressure fingers, D¹ and D², suitably spaced apart at their ends for bearing on two widely-separated teeth of the reciprocating cutter blade, while the divergent fingers, f, f, of the pres-

sure fork bear upon two intermediate teeth of the reciprocating cutter blade. The first-mentioned teeth, f¹, f², have similar small recesses, f¹⁰ and f²⁰ in the upper face, which, when the blade is of the customary form shown,—a 60 steel stamping mounted or recessed at the under side within the cutting margin of the teeth,—may be, as shown, an aperture opening through into the under side cavity of the tooth. These recesses or apertures are to afford means by which the operating lever, D, by its divergent arms, D¹ and D², may engage the reciprocating cutter blade for reciprocating it over the fixed cutter blade, A; and for such engagement the lever is furnished at the extremities of the arms, D¹ and D², with tapered pointed projections, d¹ and d², adapted to enter the recesses, f¹⁰ and f²⁰, respectively, and by their tapered form engage said recesses snugly so that there shall be no 75 lost motion in the reciprocating action.

It is extremely difficult in quantity production of such parts, on account of change of dimensions of dies, jigs, and the like, due to change of temperature, to avoid slight variation in such dimensions as the distance between the recesses f¹⁰ and f²⁰, or the distance between the projections, d¹ and d², on the divergent arms, D¹, D². And even if perfect accuracy and uniformity in these dimensions were obtained in the original production of the parts mentioned, variation of temperature occurring in the use of the tool would cause the slight variations which would be sufficient to prevent the exact registration in 90 the recesses.

To overcome this difficulty one of the projections,—as shown that on the right hand arm, D², of the lever, D,—is formed on a part, X, which is carried movably on the lever arm, D², having its movement limited to the general direction of the reciprocation of the reciprocating cutter by the lever, and restrained against movement in fore-and-aft direction with respect to the teeth. The preferred detail construction for thus associating said part, X, movably with respect to the lever arm which carries it, is as shown,—by pivoting the part, X, at its rear end to the lever arm, D², as seen at 30, the projection, d², for engaging the recess, f², being at the forward end of the part, X; so that by slight movement at said pivotal connection any inaccuracy or variation in the distance between the apertures, f¹⁰ and f²⁰, or between the ends of the 110

lever arms, D^1 and D^2 , will be accommodated, and the proper engagement of the projection, f^{20} , in the aperture d^2 , will always be secured.

It will be understood that in this construction the reciprocating blade is driven solely by the engagement of the rigid projection, f^{10} , with the recess, d^1 , of the blade; and that the only function performed by the pivotally carried projection, f^{20} , is to properly position and hold the right hand end of the reciprocating blade against fore-and-aft displacement from its proper shearing relation to the fixed cutter blade.

Preferably, as shown, the part which has the movably carried projection is not only pivoted to the lever arm, but is also housed in the under side of said arm, as shown at 40 in Figure 4, the housing being provided by a slight marginal flange, f^4 , projected downward at the end portion of the arm, D^2 , and affording the area of contact of said arm for pressure on the reciprocating blade on which said flange bears around the recess, d^2 .

It will be seen that by dimensioning the housing formed by the flange, f^4 , with respect to the projection-carrying part which it houses so that the latter shall have the needed range of movement in the direction of the shearing reciprocation of the blade and no range of movement fore-and-aft,—as in the construction shown,—the proper action for the purpose stated will be obtained independently of, and even without, the pivotal attachment of said part to the lever arm; and I do not limit myself either to the pivotal construction or to the housing for affording the desired range of movement and limiting the same in one direction and preventing movement in the transverse direction.

40 I claim:—

1. In a sheep shear and the like in combination with a fixed comb and cutter blade,

a co-operating reciprocating cutter blade and a lever by which the latter is reciprocated over the fixed blade, the reciprocated blade having recesses in its upper side for engagement by the actuating lever, and the lever having a plurality of projections for engaging said recesses, one of said projections being formed on a part carried by the lever and mounted movably thereon for movement with respect thereto at the point at which the projection is situated, in the general direction of the reciprocation of the blade.

2. In the construction defined in claim 1, the part having the last mentioned projection being pivoted to the lever and extending forwardly from its pivot, and having the projection at its forward end.

3. In the construction defined in claim 1, the projections being each tapered nearly to a point, and the recesses in the cutter blade being each dimensioned for fitting the projections at a distance back from the point of the latter substantially without play in fore-and-aft direction, and means for holding the lever pressed onto the blade when it is actuated for reciprocating the blade.

4. In the construction defined in claim 1, the lever having a laterally expanded forward end for carrying the projections to engage the blade at widely spaced positions, and having a cavity in its under face at one end of said lateral expansion the movably mounted projection-carrying part being housed in said recess with limited freedom of movement in the general direction of reciprocation of the blade and without range of movement transversely of the direction of reciprocation of the blade.

In testimony whereof, I have hereunto set my hand at Chicago, Illinois, this 24th day of August, 1927.

FREDRICK G. EVANS.
